UNITED STATES PATENT OFFICE

EDWIN M. WYATT AND KEMPER SLIDELL, OF MADISON, WISCONSIN, ASSIGNEES, BY
MESNE ASSIGNMENTS, TO AMERICAN FACE BRICK RESEARCH CORPORATION, A COR-
PORATION OF ILLINOIS

BUILDING UNIT

Application filed August 27, 1929. Serial No. 388,828.

This invention relates to a building unit which is formed from a mass of thin strings or strips of clay, which are run in parallel relation or are interlaced, interwoven, or 5 otherwise assembled into a mass of rectangular or other form, and afterwards baked or burned to produce a building unit.

The rod-like strings of which the present unit is composed are extruded from a perforated die in the form of spaghetti, the 10 diameters of which may vary, and while in the flexible or plastic state are run out in parallel relation, or are intercoiled, interlaced, or otherwise bundled, either directly 15 as they flow from the die or shortly afterwards while they are still in the wet or plastic condition.

The building unit thus composed may be used for various purposes where a light, 20 porous insulating and sound-proof material is desired. Such a unit is advantageous to manufacture, because the voids within it save material, and because the voids permit of air circulation that permits of more rapid 25 drying and burning than is possible with solid units.

Where a wall surface having a rough undulating texture is sought, the strings or continuous cylinders forming the surface 30 layers of the blocks may be allowed to remain in their matted, bundled, or intercoiled condition, undisturbed by troweling or other compressive or deformative action, so that the surfaces will display the individual 35 string-like appearance of the constituents of which the block is composed.

The building unit of the present invention may be finished in various ways, either by smoothing the surface with a troweling action 40 before drying and firing, or by extruding strips along the edges of the die, which later are brought into contact one with the other, to thus form a continuous smooth surface on all four sides of the extruding column.

Other objects and details will appear from a description of the invention, in conjunction with the accompanying drawings, wherein,—

Figure 1 is a vertical center line sectional view illustrating one of the methods of building up the unit of the present invention;

Fig. 2 is another sectional drawing showing a variation of extruding the material in a horizontal direction for building up the unit of the present invention;

Fig. 3 is a cross sectional view on the line 55 3—3 of Fig. 2;

Fig. 4 is a cross sectional view on the line 4—4 of Fig. 2;

Fig. 5 is a cross sectional view on the line 5—5 of Fig. 1; and

Fig. 6 is a partial sectional view on a somewhat larger scale, through a corner of a completed unit made at random, showing commingling of the constituent material, and with rolled or troweled down exterior 65 surfaces.

In producing the building unit of the present invention, a mass of clay A in relatively plastic condition is introduced through the hopper B of an extruding device C having an 70 auger D, which latter device, by revolving, forces the clay through a number of small orifices E of a die plate F. See Figs. 1 and 2.

The material flows from the die orifices in the form of strings resembling spaghetti, the 75 cross sectional size and configuration of which may vary, and as it flows from the die the strings are accumulated in a pile H which is preferably a continuously forming column of rectangular cross section. As shown in Fig. 80 1, this mass H may be accumulated in a trough-like mold I, where it may be built up to the desired depth by the trough passing slowly under the extending clay, so that the strings pile up in uncontrolled pattern or by 85 the trough being passed by circular, sinuous reciprocating, or other planned movement that builds the strings of clay up in matted or interwoven structure. If desired, a mold of any other form or character may be used 90 in lieu of the trough shown and described.

As shown in Figs. 2, 3 and 4, the mass H is accumulated with the strings in parallel relation to a synchronized moving belt or conveyor J. In either method, the mass is somewhat deformed and compressed by means of rollers K.

If desired, the mass can be more or less compacted by pressure from time to time, or can be compressed by any suitable means to give 100

a more accurate configuration to the mass, or if desired, the surface while still in the plastic state, may be smoothed down by troweling or the like, to give a practically continuous planate surface formation, without, however, subjecting the mass as a whole to sufficient compression to cause the strings of material to coalesce or lose their integrity. However, in view of the fact that the strings, when fed, are in a somewhat sticky or adherent condition, the mass as a whole will adhere together sufficiently to maintain its shape in preparation for the cutting, drying and firing operations.

15 In either variation of the method so far described, that is, illustrated as Figure 1 or as Figure 2, the compacted columns H are cut into suitable lengths for building units, as are stiff mud bricks, and by suitable devices, 20 or similar to those used in brick manufacture (not shown).

The mass, in the resulting form of a block made up as above described, will be dried and thereafter fired at a temperature sufficiently high to burn the material to the desired degree, which will depend more or less upon the purpose for which the block is intended. At temperatures of from 1500° F. to 1800° F., the material will be burned without fusion, 30 in most cases, but if it is desired to have the strings of material fused together, the temperature can be elevated slightly, which will fuse the material sufficiently to cause the contacting surfaces of the clay strings to fuse together, without, however, destroying the porosity of the block, due to the interstices between the strings or strips of material.

By properly regulating the atmosphere within the kiln or furnace, the surface of the 40 block may be given the desired coloration, or suitable materials may be sprinkled upon the surface, or the surface suitably scarified or impressed to impart the desired color and texture.

45 After the block has been fired to the desired degree, it is preferred to subject it to a slow cooling, to toughen the structure and prevent cracking or disintegration due to temperature shock.

50 Although the invention has been described with considerable particularity as to detail, it is to be understood that variations are contemplated, and that the drawings and description serve simply to exemplify one 55 method of carrying out the process and producing the product of the present invention.

We claim:

1. A block composed of a shaped mass of contiguous strings of fired argillaceous material adhering together at their points of contact.
2. A block composed of a shaped mass of contiguous strings of fired argillaceous material interwoven together and having the constituent strings adhered together.

3. A block composed of a shaped mass of contiguous strings of fired argillaceous material run out in parallel relation and having the constituent strings adhered together.

4. A block composed of a shaped mass of strings of fired argillaceous material massed together and having the constituent strings adhered together and the surface left relatively rough by the exposed strings.

5. A block composed of a shaped mass of strings of fired argillaceous material massed together and having the constituent strings adhered together, the surface strings presenting their exteriors in aligned relation to give to the mass a smooth exterior surface.

6. A block composed of a shaped mass of strings of fired argillaceous material massed together and adhering at their points of contact and preserving the interstices between the strings to give porosity to the block.

7. A block composed of a shaped mass of preformed particles of argillaceous material adhering together at their points of contact, and fired to form a block having interstices throughout intermediate the points of adherence.

In witness that we claim the foregoing we have hereunto subscribed our names this 26th day of July, 1929.

EDWIN M. WYATT.
KEMPER SLIDELL.
